CONTINUOUS FURNACE

Marcel Fourment, Paris, France

Application July 7, 1933, Serial No. 679,439
In France March 10, 1933

6 Claims. (Cl. 198—219)

This invention has for object a method and the corresponding arrangements for the conveyance of articles in continuous furnaces and other applications.

- 5 In most continuous furnaces now in use, the objects to be heated traverse the furnace by means of an endless hearth conveyor consisting either of two endless chains whose links support transverse plates or a grating.
- 10 This mode of conveyance is attended by the great disadvantage that the hearth is cooled when it issues from the furnace and must be heated again with the articles that it carries when it enters the furnace; the calories taken up by the hearth during its passage in the furnace are then dissipated in pure waste.

Moreover, in certain cases, the cold hearth must enter the hottest part of the furnace and its temperature can equal that of the furnace 20 only after a certain working time, and this is clearly disadvantageous as regards the utility of the furnace.

There have been invented also furnaces called "beam" furnaces in which the advance of the 25 articles is obtained by what may be called longitudinal beams or girders which rise and fall periodically in channels provided in the hearth or sole of the furnace; this remedies the disadvantages mentioned above, but this method, 30 in the different modes of carrying it into effect hitherto known, renders possible the transportation only of articles of fairly large dimensions; when small articles are to be reheated, it is necessary to place them on trays and the disadvantages 35 mentioned above (dead weight to be heated) are again met with aggravated by complication in management and in maintenance.

In the method of conveyance of articles for continuous furnaces forming the subject matter 40 of the present invention, which remedies these disadvantages, there is used a double group of bars or cables for the purpose of producing by elementary advances the progress of articles, even of small dimensions, through the furnace. These 45 bars or cables are placed parallelly to one another so that there is only a very small space between each of them in order that articles of small dimension may be supported without there being danger of their passing through the hearth thus constituted.

In the accompanying drawings, which represent by way of example a form of construction of a conveyor applied to a continuous furnace:—

55 Fig. 1 is a longitudinal section of the furnace,
Fig. 2 is a plan view partly in section,
Fig. 3 is a partial sectional view of the hot end of the furnace,
Fig. 4 is a transverse section of the furnace,
80 Figs. 5, 6 and 7 show the different groups of

eccentric pulleys supporting the bars or cables, and

Fig. 8 shows the system of gearing of the shafts carrying the eccentric pulleys,

Fig. 9 is a diagrammatic general vertical section of a modification,

Fig. 10 is a section corresponding to II—II of Fig. 9.

Fig. 11 is a modification of Fig. 10 showing another controlling arrangement.

According to the invention, the furnace 1 of the type called a "continuous furnace"—i. e., of the type in which the articles to be heated or reheated are given a continuous progressive movement from one end of the furnace to the other—comprises secondary transverse shafts 2, which are of any suitable number and are mounted in any suitable manner by means of bearings. Each of these shafts has fixed to it eccentric pulleys 3, 4, which are mounted eccentrically on it, have all the same eccentricity, but are displaced in relation to each other by 180° as is shown in Fig. 6, so that for a given position of the shaft 2, the pulleys 3 for example the even-number pulleys on the shaft are in a high position and the odd-number pulleys 4 are in a low position.

Each shaft 2 carries also at its free end, which is outside the furnace, a chain wheel 5 that serves for its operation.

These pulleys 3 and 4 have their peripheries 30 suitably formed so as to present a channel in which a bar or a metallic cable 6 or 7 can rest, the whole of the bars or cables being thus divided into two groups of which one group, that composed of the bars 6 for example, bears on the 35 eccentricities that are in a high position at a given moment, and the other group, that composed of the bars 7, on the eccentricities then in a low position.

At the cold end of the furnace there is arranged transversely a shaft 8 carrying likewise eccentricities of a number equal to that of the pulleys 3, 4 of each shaft 2 and having for example the same eccentricity. These eccentricities are keyed on the shaft 8 and are likewise displaced in relation to one another by 180° so that in a manner analogous to that of the pulleys of the shafts 2, at a given moment the even-number eccentricities may be for example in a high position and the odd-number eccentricities in a 50 low position.

On these eccentricities there are mounted straps 9 to which are fixed the bars 6 and 7 whose other ends are connected by means of springs 10 to an angle-iron 11 rigidly attached to the frame of the furnace. These springs (for example helical springs) should have suitable characteristics so as to maintain the bars or cables sufficiently stretched notwithstanding their weight and that of the articles carried, and to be capable of sus- 60

taining an elongation determined by the diameter of eccentricity of the eccentrics mounted on the shaft 8 and of compensating for the stretching of the bars or cables.

5 The shaft 8 receives its movement from a motor 13 through a suitable speed reducer 14 of any desired type and through suitable transmission gear; moreover, this shaft carries likewise a chain wheel similar to each of the chain wheels 5 carried by the shafts 2 and an endless chain 12 links all the shafts 2 firmly up with the shaft 8.

10 The endless chain 12 may have any suitable tension device such as wheels 15 (Fig. 8) which are mounted on brackets 16, and the position as 15 to height of which is capable of regulation so as to secure the proper coming into engagement of the chain with the motor wheels 5.

15 As all the shafts 2 and 8 are keyed in the same angular position in relation to one another so that 20 all the even-number eccentrics and pulleys of each of the shafts are at the same time in a high position for example whilst all the odd-number eccentrics or pulleys are in a low position, or vice-versa, the bars resting on these pulleys form 25 two platforms or hearths of which one is in a high position while the other is in a low position and each of which can be given a movement of translation under the action of the shaft 8.

30 The trajectory described by a point on a bar or on a cable is a circle the diameter of which is equal to that of the eccentricity (sic) of the pulleys; but if it were considered necessary the mechanism could be modified so that this trajectory would be an ellipse, a rectangle, or any other figure.

35 The furnace may comprise any suitable heating arrangement. In the example shown, burners such as 17 are arranged at one of the ends of the furnace and at the upper part, the hot gases circulating about the articles to be treated 40 through conduits 18 (Fig. 4) to pass under the sole 19 of the furnace and afterwards to be delivered to the flue 20.

The operation is as follows:—

45 When the motor operates the shaft 8, and, by means of the chain 12 and the wheels 5, the shafts 2, all these shafts have the same movement in space and in time. Each of the groups of even-number or odd-number bars or cables forming the two platforms or hearths then has a rotational movement in a vertical plane, these two 50 rotational movements being displaced in relation to each other by 180°. It will thus be seen that an article placed on the conveyor thus constituted is raised by the group of even-number bars, for 55 example, which communicates to it a slight forward progression. When this group of bars descends again, the other group of bars rises, picks the article up again, and causes it to execute a fresh forward progression, after which the first 60 group of bars comes into action again. For one revolution of the motor shaft 8, each article thus progresses by an amount equal to double the diameter of the circle of eccentricity of the eccentrics mounted on the shaft 8.

65 The respective diameters of the eccentrics carried by the shafts 2 and by the motor shaft 8 determine the form of the movement of the platforms or hearths, this movement being circular in the case in which all the eccentrics have the same diameter and elliptical in the case in which the diameter of the eccentrics 8 differs from the diameter of the eccentrics 2, so that the form of the movement can be varied according to requirement to obtain a progression with a more

or less pronounced movement of ascent and descent of the articles to be conveyed.

Moreover, in order to obtain a more continuous movement of the articles to be conveyed, there might be employed more than two groups of cables or bands, the conveyance then taking place more regularly.

10 The system for transmitting movement to the shafts 2 might be different from that described; the system comprising a worm and motor shaft 10 might be used and would not present the inconvenience of having to take up play.

15 This conveying arrangement avoids the losses of heat due to the successive reheating and re-cooling of the conveying hearth that are inevitable when the conveyor is constituted by an endless hearth, entering and issuing from the furnace continually. Moreover the bars or cables and also the eccentric pulleys may be given thicknesses as small as possible. Grating may be constituted of bars sufficiently close together capable of supporting articles of any desired dimensions so that it is not necessary to convey the articles to be heated in cases which must also be heated and thus involve loss of heat.

20 Finally, furnaces of any desired length may be made by arranging as many secondary shafts 2 as may be necessary for supporting the cables.

25 There may be used any system of heating, whether employing solid, liquid or gaseous fuel, 30 or employing electric resistances.

The invention is applicable for the conveyance of articles in furnaces and for all other applications.

35 In the form of carrying out the invention shown in Figs. 9 to 11, the surface of the wires or bars supporting the objects to be moved and constituting a platform is divided into two sections 21 and 22 which engage motive elements such as drums or other motive elements 23 and 24 mounted on different shafts 25 and 26 and controlled either by a common motive element or by different motive elements enabling rotational movements of any desired sense to be impressed on the shafts 25 and 26.

40 The shafts 25 and 26 being put into rotation in the same sense, the apparatus works as in the case of Figs. 1 to 8—i. e., the articles arranged at the entry end 27 of the furnace will be carried in the interior of the furnace from right to left and will 50 arrive at the opposite end of the furnace 1.

45 If, on the contrary, the shaft 26 is caused to rotate in a sense different from that of the shaft 25, there will be produced, by the section 22 of the platform, a direction of circulation different from 55 that of the section 21.

50 In the particular form of construction indicated in Fig. 10, an article placed on the platform section 21 at the left-hand end of the furnace, will proceed to the right-hand end of this 60 furnace, whilst an article placed on the platform section 22 at the right-hand end will proceed to the left-hand end of the furnace.

55 Such an arrangement is particularly useful for producing the progressive heating of certain articles up to a predetermined temperature and for submitting these articles afterwards to a progressive cooling.

65 In order to produce a treatment of this nature with the constructional form of the arrangement according to Figs. 9 to 11, the articles are placed at the right-hand end of the furnace on the section 22 of the platform, the said articles being subjected to a progressive heating as far as the left-hand end of the furnace, where a mechanical 75

arrangement or a manual operation will cause the articles to pass from the section 22 onto the section 21 of the platform.

This section being moved in the direction opposite to that of the section 22, the articles will be brought back towards the right-hand end of the furnace, being subjected during their travel to a progressive cooling. There is thus brought about an excellent thermic cycle, for the articles, which are cooled during their carriage by the platform section 21, give up a large part of their calories to the articles that are being heated during their carriage by the platform section 22.

This form of execution of the arrangement thus enables one of the three following thermic cycles to be obtained by simply changing the sense of rotation of the controlling shafts 25 and 26:—

1. Progressively heating articles from the ordinary temperature to a predetermined temperature at which they are removed from the furnace. This is the case for example of the problem of the tempering, the annealing, the hardening, etc. of metallic parts.

2. Annealing articles or parts which are placed not into the furnace and which should be cooled progressively according to a predetermined law; this is the case for example of the annealing of glass articles that have just been made.

3. Heating articles progressively from the ordinary temperature to a predetermined temperature and bringing them back afterwards progressively to the ordinary temperature. This is the case for example of decoration on glass or of the thermic treatment of metals and alloys.

The platform of the furnace might be divided into any desired number of sections each having its own controlling shaft.

There might for example, as indicated in Fig. 11, be provided a central section 28, with its shaft 29 and lateral sections 30, 31 which are of a width equal to or different from that of the central section 28 and are adapted to be controlled either by a common shaft 32 or by different shafts provided with operating arrangements enabling them to be operated in the same sense as the central shaft 29 or in a sense different from that of the rotation of this shaft and at an equal or different speed.

50 What I claim is:—

1. In a device for conveying articles to be treated in continuous furnaces, a number of groups of bars forming platforms, external drive means for causing said groups of bars to receive each in turn a longitudinal horizontal advance movement in at least one direction, internal means independent of said first mentioned means for causing said bars to receive a vertical movement, while being horizontally moved, and means for maintaining the bars under tension and tending to move them in a direction opposite to that imparted by the drive means, while permitting said bars at all times to elongate under the influence of the driving mechanism.

65 2. In a device for conveying articles to be treated in continuous furnaces, a number of groups of bars forming platforms, a controlling shaft located at one end of the furnace and external to said furnace, cams keyed on said shaft, straps connected with said cams, bars secured to said straps, internal means independent of said first mentioned means for causing said bars to receive a vertical movement, while being horizontal-

tally moved in at least one direction, and means for maintaining the bars under tension and tending to move them in a direction opposite to that imparted by said controlling shaft, while permitting said bars at all times to elongate under the influence of the drive from said control shaft.

5 3. In a device for conveying articles to be treated in continuous furnaces, a number of groups of bars forming platforms, a controlling shaft located at one end of the furnace and external to said furnace for positively moving the bars in at least one direction, cams keyed on said shaft, straps connected with said cams, bars secured to said straps, a number of transverse shafts located in the furnace, groups of cams keyed on said transverse shafts and synchronized with said external shaft, and means for maintaining the bars under tension and tending to move them in a direction opposite to that imparted by the controlling shaft, while permitting said bars at 10 all times to elongate under the influence of the driving mechanism actuated by said controlling shaft.

15 4. In a device for conveying articles to be treated in continuous furnaces, a number of groups of bars forming platforms, a controlling shaft located at one end of the furnace and external to said furnace for positively moving the bars in at least one direction, cams keyed on said shaft, straps connected with said cams, bars secured to said straps, a number of transverse shafts located in the furnace, groups of cams keyed on said shafts and synchronized with said external shaft, springs located at a point remote from the controlling shaft, for maintaining the bars under tension and tending to move them in the direction opposite to that imparted by the drive means actuated by the control shaft, while permitting said bars at 20 all times to elongate under the influence of the driving mechanism actuated by said controlling shaft.

25 5. In a device for conveying articles to be treated in continuous furnaces, two groups of thin bars placed sidewise adjacent with each other without undue clearance, external means for causing said groups of bars to receive each in turn a longitudinal horizontal advance movement in at least one direction, internal means independent of said first mentioned means for causing said bars to receive a vertical movement, while being horizontally moved, and means for maintaining the bars under tension and tending to move them in a direction opposite to that imparted by the drive means, while permitting said bars at 30 all times to elongate under the influence of the driving mechanism.

35 6. In a device for conveying articles to be treated in continuous furnaces, two groups of thin bars placed sidewise adjacent with each other without undue clearance, external means for causing said groups of bars to receive each in turn a longitudinal horizontal advance movement in at least one direction, internal means independent of said first mentioned means for causing said bars to receive a vertical movement, while being horizontally moved, and means for maintaining the bars under tension and tending to move them in a direction opposite to that imparted by the drive means, while permitting said bars at 40 all times to elongate under the influence of the driving mechanism.

45 7. In a device for conveying articles to be treated in continuous furnaces, two groups of thin bars placed sidewise adjacent with each other without undue clearance, external means for causing said groups of bars to receive each in turn a longitudinal horizontal advance movement in at least one direction, internal means independent of said first mentioned means for causing said bars to receive a vertical movement, while being horizontally moved, and means for maintaining the bars under tension and tending to move them in a direction opposite to that imparted by the drive means, while permitting said bars at 50 all times to elongate under the influence of the driving mechanism.

55 8. In a device for conveying articles to be treated in continuous furnaces, two groups of thin bars placed sidewise adjacent with each other without undue clearance, external means for causing said groups of bars to receive each in turn a longitudinal horizontal advance movement in at least one direction, internal means independent of said first mentioned means for causing said bars to receive a vertical movement, while being horizontally moved, and means for maintaining the bars under tension and tending to move them in a direction opposite to that imparted by the drive means, while permitting said bars at 60 all times to elongate under the influence of the driving mechanism.

65 9. In a device for conveying articles to be treated in continuous furnaces, two groups of thin bars placed sidewise adjacent with each other without undue clearance, external means for causing said groups of bars to receive each in turn a longitudinal horizontal advance movement in at least one direction, internal means independent of said first mentioned means for causing said bars to receive a vertical movement, while being horizontally moved, and means for maintaining the bars under tension and tending to move them in a direction opposite to that imparted by the drive means, while permitting said bars at 70 all times to elongate under the influence of the driving mechanism.

MARCEL FOURMENT.
